UNITED STATES PATENT OFFICE.

LEWIS RAYMOND, OF NEW YORK, N. Y.

IMPROVED VALVE FOR LIFE-BOATS.

Specification forming part of Letters Patent No. 40,279, dated October 13, 1863.

To all whom it may concern:

Be it known that I, LEWIS RAYMOND, of the city, county, and State of New York, have invented a new and useful Improvement in Life-Boats; and I do hereby declare that the following is a full, clear, and exact description of the same, reference being had to the accompanying drawings, in which—

Figure 1 represents a plan of a ball-valve and jacket turned upside down, and Fig. 2 represents a section of a portion of a self-voiding life-boat constructed according to the principles of my improvements.

Previous to my invention life-boats have been constructed with self-acting clack-valves for the purpose of permitting the escape of water from their interiors, but such boats have frequently been found to be unserviceable after being kept long out of the water from the rigidity of the hinges that connected the valves with their seats.

The object of the present invention is to obtain a self-voiding boat which is not liable to this defect and possesses greater efficiency as a water-voider than those made heretofore.

To this end my invention consists in the combination of the shell of the boat with a ball-valve, and with a jacket within which the valve moves. By this combination a more certain voiding of the water from the boat takes place than has heretofore been attained, coupled with a more certain self-closing of the water-way by the valve, because the free passage of water around all of its sides is not obstructed by any hinge or other connection of the valve with the boat, and the freedom of movement of the valve in closing is not obstructed, as it is in clack-valves, by the rigidity of a hinge.

The best mode with which I am acquainted of carrying my invention into effect is to construct the ball-valve of india-rubber and hollow, and to inclose it in a suitable jacket, such as is shown in the accompanying drawings, before combining it with the boat; also, to divide the boat into a series of water-tight compartments, each of which has a valve and jacket appertaining to it.

The valve, as represented at D in the drawings, should be perfectly spherical, and the jacket should be composed of two parts, one of which, C, forms a grating that permits the escape of water, but retains the valve. The

other part of the jacket, A, has an opening in it sufficient to permit the protrusion of about one-quarter of the valve. It has also a broad flange, B, which overlaps the opening made in the shell of the boat to receive the jacket. The grate C is screwed into the part A of the jacket, and is fitted with guide-pins 1 to guide the ball-valve in moving to and fro in the jacket. The jacket with the valve within it is secured to the shell of the boat by means of rivets or screws passed through suitable holes in the flange B.

This valve can be applied to any boat by dividing the bottom of the boat on the inside into water-tight sections, into which the water which is inside the boat is allowed to flow by means of an ordinary leather or wooden clapper suspended by a hinge, such clapper opening into the section.

As many valves may be used as is desired, and each valve is placed in a water-tight section. There ought always to be about eight valves, and more will be advantageous in boats intended to be used in heavy seas. The number of valves will also depend on the size of the boat.

The valve is placed a few inches below the light water-line of the boat, and two should be placed on each side of the keel near the bow and stern, and the others about the bilge streaks, midships, and forward and aft of midships.

When the boat is entirely on an even keel, the pressure of the water on the outside of the boat against the ball forces it into the position designated by E, and closes the opening from the interior of the boat.

When the boat is made to roll or rock to one side by the action of the sea or other means, the water which may be in it, pressing against the clappers on the lower side, forces its way into the water-tight sections, and when the boat rolls or rocks to the other side the clappers are closed by the pressure of the water against them, and the pressure of the water on the ball forces it into the position designated by D, and the water in the sections on the upper side of the boat escapes, until, by the rolling of the boat back again, the ball is forced up by the pressure of the water on the outside again into the position E, and the water on the inside again begins to find its way into the sections which are now on the lower side.

Similar valves and water-tight sections being placed on the opposite side of the boat, there will be a constant escape of water from that side of the boat which is the most elevated.

The valves which are placed at the ends of the boat being also provided with similar water-tight sections, arranged as above described, the water will accumulate in the bow as that plunges into the sea and will escape as it rises, and the water will accumulate in the stern as it becomes depressed and escape as it rises.

It is obvious that a life-boat constructed with this combination will always be fit for use however long it may have been out of water, because the valves lying loose in the jackets are always free to close when the boat is placed in the water.

When it is intended to use this valve instead of a plug or plugs, merely to drain a boat when hoisted, two valves may be used, one on each side of and close to the keel. When the boat is hoisted out of the water, the balls drop into the position designated by D, and any

water that may be in the boat is allowed to escape; and when the boat is again lowered into the water the pressure upon the ball forces it up into the position designated by E, and the opening from the interior of the boat is closed.

Having thus described the best mode with which I am acquainted of carrying my invention into effect, it is proper to state that I do not claim to be the inventor of a ball-valve, but

What I claim as my invention, and desire to secure by Letters Patent, is—

The combination of the shell of the boat, ball-valve, and jacket, substantially as described, the whole constituting a self-voiding boat.

In testimony whereof I have hereunto subscribed my name.

LEWIS RAYMOND.
